Primary Examiner — Kevin Rudzinski*Assistant Examiner* — John Reickel(74) *Attorney, Agent, or Firm* — Kilpatrick Townsend & Stockton LLP(57) **CLAIM**

The ornamental design for a display screen with a graphical user interface, as shown and described.

DESCRIPTION

The FIGURE is a front view of a display screen with a graphical user interface, showing my new design.

The broken line showings of the control unit are included for the purpose of illustrating environmental structure and form no part of the claimed design.
